UNITED STATES PATENT OFFICE.

ALBERT A. WILKINS, OF MIDDLETON, MASSACHUSETTS, ASSIGNOR OF ONE-HALF TO CHARLES E. CAMPBELL AND FREDERICK R. CAMPBELL, BOTH OF LYNN, MASSACHUSETTS.

PROCESS OF RENEWING FILAMENTS IN LAMPS.

1,202,136.

Specification of Letters Patent.

Patented Oct. 24, 1916.

Application filed April 2, 1914. Serial No. 828,982.

To all whom it may concern:

Be it known that I, ALBERT A. WILKINS, a citizen of the United States, residing at Middleton, in the county of Essex and State of Massachusetts, have invented certain new and useful Improvements in Processes of Renewing Filaments in Lamps, of which the following is a specification.

My invention relates to improvements in processes of renewing filaments in lamps, and the object of my improvement is to provide means for renewing the filaments of incandescent lamps that are suitable for use with lamps having tungsten filaments of the type connected in circuits of fairly high voltages and in which the filament is of appreciable length.

In the accompanying drawing, Figure 1 is a side elevation of a lamp having a broken filament and which is to be renewed by my process. Fig. 2 is a similar view of the same in the tubulated condition, and with a holder for the tubulated end and a holder for the base end indicated by broken lines. Fig. 3 is a similar view of the same after having a flame applied to the side wall and the upper part raised and separated from the lower part. Fig. 4 is a similar view of the lower or base part with a new filament applied thereto. Fig. 5 is a similar view showing the upper and lower parts reunited. Fig. 6 is a similar view of the refinished lamp.

The lamp shown in Fig. 1 is of the ordinary tungsten type and comprises a bulb having the tip 11 at the upper end and provided with a base 12 at the lower end and in which is housed a filament 13, shown as broken in the said figure, and suitable supports for the said filament 13. The said supports comprise a post 14 of glass extending axially from the stem 15, adjacent the base end, and upwardly for an appreciable portion of the interior space of the bulb 10, and two sets of arms supported by the said post 14 and projecting radially therefrom, respectively a set of lower arms 16, adjacent the stem 15 and a set of upper arms 17 at the extreme upper end of the post 14.

The filament 13 is normally strung back and forth between the arms 16 and 17, the ends thereof being connected to the leading in wires 18, supported from the stem 15.

The first step in the process of renewing the filament 13 is preferably to tubulate the lamp in an ordinary manner by connecting a tube 19 at the tip 11. A holder 20 may be provided for the base 12 and a holder 21 for the tube 19.

In the next operation the lamp is revolved and a fine flame is applied to the side wall 22 until the material of the side wall, which of course is glass, softens, after which the upper portion 23 is raised from the lower portion 24, the glass at the line of rupture being drawn out quite thin, on both the upper portion 23 and the lower portion 24. The upper portion 23 is then removed clear of the lower portion 24, after which the new filament 13 is readily put in place and mounted on the proper supports. Then the upper portion 23 of the bulb 10 is reconnected to the lower portion 24, the junction 25 of the opposed edges of the said two portions being sealed by the application of heat, and which operation may be effected by a specially constructed machine seal, the operation itself being facilitated by the fact that the two edges united are the same that were originally severed, and also by the fact that the said edges are drawn quite thin, as mentioned, in the operation of separating the said upper and lower portions. Other means of separation of the two portions may be employed, such as the use of a diamond, but this is not so desirable because the same leaves a relatively thick edge and results in an excessive amount of breakage.

The junction 25 of the upper portion 23 and the lower portion 24 in the renewed lamp will in most cases be less smooth and uniform than the adjacent original wall 22. For this reason I prefer to divide the bulb 10 along a radial plane adjacent the set of lower supporting arms 16 that support the filament 13 or between the same and the base 12 so that the junction is removed from the normal radiating zone of the filament 13.

After the two portions 23 and 24 have been reunited as described the lamp is exhausted by means of the tube 19 and a new tip 11 formed.

It is evident that the process described for the renewal of filaments is particularly advantageous in the renewal of tungsten filaments such as are used for ordinary com-

mercial voltages, and which filaments are quite long and are distributed about considerable of the space inclosed by the bulb.

What I claim as my invention is:—

- 5 The process of renewing the filament of an incandescent lamp having a filament housed in a glass bulb, comprising heating a limited zone extending around the body portion of the said bulb by means of a relatively fine flame, elongating the material of the said zone while so heated so as to draw the said material relatively quite thin, separating the two parts of the said body
- 10 portion by cracking the said drawn material of the said zone, operating on the filament while the said parts are so separated, and reuniting the said parts by sealing together the edges of the material of the zone, whereby the said body portion will be restored substantially as before the said parts 20 were separated.

ALBERT A. WILKINS.
